FUEL BURNER

Frank V. Risinger, Lakewood, Ohio

Application October 3, 1930, Serial No. 486,221

21 Claims. (Cl. 158—63)

The present invention relates to the art of hydrocarbon burning apparatus and appliances and involves an apparatus for burning, in gaseous or vaporized condition, a liquid hydrocarbon mixed with air. One of the most available hydrocarbons at present on the market is gasoline, and it is highly desirable to produce, if possible, a burner appliance and method of burning a hydrocarbon of this nature for household, furnace, and any other uses required. The methods and equipment proposed by the prior art have been open to a decided disadvantage, owing to the fact that the inherent danger attendant upon the utilization of a highly volatile fuel such as gasoline, has not been entirely eliminated, and furthermore, it has been difficult to prevent condensation of the vaporized fuel before it reaches the burner openings.

The present invention deals with a modification of the apparatus described and claimed in the copending application of Frank V. Risinger, Serial No. 458,327, filed May 31, 1930, and has for its object the provision of an apparatus which will efficiently burn highly atomized or vaporized hydrocarbon fuel, such as gasoline, the apparatus being of such a nature as will adapt it for use in domestic household appliances such as stoves, furnaces, and the like, and which can be installed at a relatively low cost.

To accomplish this object, an auxiliary reservoir proposed in the said identified application is constructed in the form of a manifold, which may be readily incorporated into the stove structure in an advantageous and commercially adaptable form, the manifold supplying fuel to the burners in a highly carbureted and vaporous condition, the manifold being provided with means for maintaining a predetermined quantity of hydrocarbon therein which is supplied from a main reservoir under air pressure as the fuel in its vaporous form is being withdrawn from the manifold.

Other and further objects and advantages of the invention will become apparent as the description of the invention proceeds.

The invention will be more readily understood by reference to the accompanying drawings, in which—

Figure 1 is a plan view of an installation made in accordance with the present invention.

Figure 2 is a view, partly in section, taken along the line 2—2 of Figure 1.

Fig. 2a is a view, partly in section, taken along the line 2a—2a of Fig. 2.

Fig. 2b is a view, partly in section, taken along the line 2b—2b of Fig. 2.

Figure 3 is a sectional view through the auxiliary reservoir, taken on the line 3—3 of Figure 1.

Figure 4 is a view along the line 4—4 of Figure 1, looking in the direction of the arrows, and

Figure 5 is a fragmentary side sectional view of the hydrocarbon supply tank, showing the arrangement of air and liquid supply lines therefrom.

Referring more particularly to the drawings, A indicates generally the improved hydrocarbon vapor burners, which are supplied with hydrocarbon fuel vapor in a highly carbureted state from the auxiliary carbureting receptacle B, which forms a manifold, as above mentioned.

The main supply tank indicated at C is preferably disposed exteriorly of the building in which the burners A and auxiliary reservoir or manifold B are located, the supply tank C being provided with the filling opening 11 having a suitable closure plug 12 and means for supplying air under pressure thereto through a pipe 13, consisting of a compressor 14 operated by any suitable power source, such as a motor 15. Associated with the compressor is a pressure responsive controlling device 16 for discontinuing the operation of the motor and compressor when the pressure in the system reaches a predetermined degree, and starting again when the pressure goes below a predetermined degree.

The main supply tank C has leading therefrom a fuel delivery pipe 17 and an air delivery pipe 18. These pipes communicate with the interior of the manifold B. Pipes 17 and 18 terminate in seats at the manifold ends for needle valves 19a and 19b, respectively, these valves being actuated by a float 19, pivotally supported at 20.

It will be seen that the auxiliary receptacle or manifold B is illustrated as having the general form of a T, although the particular shape may be changed to meet needed requirements for installation. In the illustrated form, the stem of the T has two branches 21 and 21a which receive the similar conduits 24 and 24a, respectively, which conduits form generator tubes for vaporizing the fuel, which fuel passes into these conduits from the branches 21 and 21a through valves illustrated by 26 in Figure 2, which figure also shows that each conduit 24 and 24a has a rod 25 passing through it, the rod terminating in the needle valve 25a, the regulation of which controls the amount of fuel passing through its conduit. It will be noted that the generator

tubes 24 and 24a are positioned so as to be heated by the burner flames after the burners are lighted.

Disposed within the branches 21 and 21a respectively, are fuel carbureting or atomizing devices 22, each of these devices consisting of a U-shaped pipe having one end in communication with a passageway 30 in valve 26 and the other end disposed above the level of the liquid as indicated at 22b. The pipe extends downwardly intermediate its ends well below the level of the liquid and is provided with a small fuel receiving opening 22a. The passageway 30 communicates with the conduit 24. When the burner 21 is in operation, the pressure within the manifold B causes air to flow through the open end 22b downwardly past the opening 22a, and upwardly into the passageway 30. Pressure on the liquid within the manifold B also causes a certain amount of the liquid to pass into the opening 22a, but due to the relatively minute size of this opening, the liquid is completely atomized or vaporized by the air passing through the pipe before it reaches the passageway 30. The valve 25 is provided with an auxiliary passageway 31—32 for admitting additional air under pressure from the manifold B into the vaporous mixture as it is conveyed through the passageway 30 in the valve, the quantity of such additional air being controlled by the valve control handle 23.

As above mentioned, each burner includes a needle valve 25a, the conduit 24 extending laterally and having the valve 26 secured thereto. Adjustment of the valve 25a is accomplished by operation of the handle member 28 which increases or decreases the space through the nozzle outlet. The fuel first in a mist-like form, then in vaporous form after the burners are started is injected into the Bunsen burner 27, containing a gas chamber 29 whereupon it passes through the burner openings and is burned in the usual manner, the flame passing around the conduit 24 to heat the incoming fuel.

It will be noticed that the vaporous fuel as it is injected into the end of each Bunsen tube 27 causes the necessary additional air for proper combustion of the fuel to be sucked in therewith adjacent to the jet 25a.

Fuel will continue to flow through the pipe 17 until the level of the fuel rises to a point where the float control valve member 19 will be lifted. This action seats the valve 19a over the fuel line and vents the pipe 18, permitting air under pressure from the supply tank C to pass through the pipe 18 into the manifold B which will equalize the pressure between the supply tank and manifold.

When the level drops sufficiently within the manifold B the float 19 will again close the valve 19b at the end of pipe 18, causing a reduction of pressure between the manifold and the tank whereupon the higher pressure in the tank will again force the liquid upwardly through the pipe 17 until the level is again established.

The carbureting device or atomizer 22 consists of a U-shaped pipe having one end in communication with a control valve 23 and the other end disposed above the level of the liquid as indicated at 22b. The pipe 22 extends downwardly intermediate its ends well below the level of the liquid and is provided with a small fuel receiving opening 22a.

When the burner is in operation the pressure within the manifold B causes air to flow through the open end 22b downwardly past the opening

22a and upwardly into the control valve 23. Pressure on the liquid within the manifold B also causes a certain amount of the liquid to pass into the opening 22a, but due to the relatively minute size of the opening the liquid is completely atomized or carburetted by the air passing through the plate before it reaches the valve 23. If desired, the valve 23 may be provided with an auxiliary air supply control valve for admitting additional air under pressure from the manifold B into the atomized mixture as it is conveyed from the valve through the conduit 26 through the burner A.

It may also be here noted that this apparatus permits complete carburettion of the fuel without the necessity of the preheating, and it conveys the fuel to the burner in this carburetted condition whereby it may be immediately ignited and thus readily employed for burner starting purposes, even though subsequently it may be heated additionally to increase its vaporized condition in which it will be burned during the continuous use of the burner. This presents a marked advantage over the prior art, which has always proposed to convey the fuel in a liquid state to the burner, whereupon it is introduced into a generator tube which must be maintained heated to a comparatively high degree in order to vaporize the fuel before it enters the burner. This prior art construction usually necessitates the preheating of the generator tube, which positively prevents immediate ignition and positive control of the vaporized fuel as it enters the burner.

In the present apparatus there is obtained a most flexible control of the richness of the ultimate gas generated from such liquid hydro-carbons as gasoline for which the invention has been especially designed. Thus there is effected a preliminary automatic admixture of air from the main liquid fuel supply tank with the rich fuel in the auxiliary manifold fuel reservoir, a supplemental mixture of air under manipulatable control of the vaporized fuel produced in the auxiliary reservoir and further additional admixture of atmospheric air with fuel quantity control, with an already highly vaporized fuel, at the location of the vapor jet or jets 25a from which the vaporous fuel is injected into the heating or Bunsen pipes 27 and 27a. The nicety of control thus obtained makes for the generation of a pure fuel vapor direct from liquid fuel, such as gasoline, in a manner not heretofore secured. The disadvantages of being required to burn a poorly developed and largely moist fuel gas so generally produced by burning apparatus of the type of this invention are thus largely obviated, along with carbon troubles and consequent inefficiency.

It will be understood that the description given above for the construction and operation of the device for one burner is similar for each burner in the appliance. The illustration shows four burners, of a type such as is illustrated in Figure 2. It will be seen that each end of the cross of the T can be connected to other burners if desired, as for instance an oven (not shown); and it will also be apparent that the illustrated form is merely one example of the several forms which the invention may take, and that many details of construction can be changed without departing from the inventive concept. It will be accordingly understood that it is intended and desired to embrace within the scope of this invention such modifications and changes as may be

necessary to adapt it to varying conditions and uses. I have referred to the member B as an auxiliary receptacle or manifold, and where this term is used in my appended claims it is to be viewed in the light of its meaning as an auxiliary receptacle, because, obviously, my invention is not necessarily limited to the use of a manifold that must operate in conjunction with a plurality of burners. It is clear that the member B with the extending branches 21 and 21a 10 is designed for supplying a single burner just as much as for a plurality of burners. Its primary function is to act as an auxiliary fuel and air receptacle and it is therefore not desired that my claims be limited to a member B designed to supply a plurality of burners, but rather to such a member acting as an auxiliary receptacle for supplying one or more burners.

Having thus described my invention, what I 20 claim as new and desire to secure by Letters Patent of the United States, is—

1. In a hydrocarbon burning apparatus, the combination with a plurality of hydrocarbon burners, of a manifold for delivering hydrocarbon fuel to the burners, the said manifold forming a fuel supply reservoir for containing a supply of liquid fuel, means associated with the manifold for atomizing the said fuel for each burner, means for supplying fuel and air to the manifold, 30 and means for controlling the fuel and air supplies, the operation of the said means being determined by the level of the liquid in the manifold.

2. In a hydrocarbon burning apparatus, the combination with a plurality of hydrocarbon burners, of a manifold for delivering fuel to the burners, the said manifold forming a reservoir for containing a supply of liquid fuel, means associated with the manifold for atomizing the said fuel for each burner, means for supplying fuel and air to the manifold, and means for controlling the fuel and air supplies comprising valves operated by the level of the liquid in the manifold.

3. In a hydrocarbon burning apparatus, the combination with a plurality of hydrocarbon burners, of a manifold forming a reservoir for a supply of liquid fuel for the burners, means for introducing liquid fuel and air to the said manifold, and means within the manifold for controlling the fuel and air supplies, the said means comprising valves actuated by the level of liquid fuel in the manifold.

4. In a hydrocarbon burning apparatus, the combination with a plurality of hydrocarbon burners, of a manifold forming a reservoir for a supply of liquid fuel for the burners, means for introducing liquid fuel and air into the said manifold, and means within the said manifold for controlling the fuel and air supplies, the said means comprising a float controlled by the level of liquid fuel within the said manifold, and valves operated by the said float.

5. In a hydrocarbon burning apparatus, the combination with a plurality of hydrocarbon burners, of a manifold for the burners and forming a reservoir for a supply of liquid fuel for the burner, fuel and air lines leading into the manifold, means within the manifold for controlling the fuel and air lines, the said means comprising a float controlled by the level of liquid fuel within the manifold, and a valve for each line operated by the float, and means for atomizing the fuel for each burner.

6. In a hydrocarbon burning apparatus, the

combination with a plurality of hydrocarbon burners including a heating tube, of a manifold for the burners, the manifold having openings therein, one for each burner, the manifold forming a reservoir for a supply of liquid fuel for the burners, air and fuel lines leading into the manifold for admission of air and fuel thereto, means adjacent each line for controlling the said admission responsive to variation in the fuel level in the manifold, means adjacent each burner opening in the manifold for atomizing the fuel into a mist-like condition as it passes to the respective burners, and means for preheating the fuel after atomization to vaporize the atomized fuel while passing through the heating tube. 15

7. In a hydrocarbon burning apparatus, the combination with a plurality of hydrocarbon burners, of a manifold for the burners, the manifold having openings therein, one for each burner, the manifold forming a reservoir for a supply of liquid fuel for the burners, air and fuel lines leading into the manifold for admission of air under substantial pressure and fuel thereto, means for controlling the said admission, the said means comprising a float controlled by the level 20 of liquid in the manifold and a valve for each line operated by the float, and means adjacent each burner opening in the manifold for atomizing the fuel passing to the respective burners.

8. A hydrocarbon burning apparatus which 30 comprises the combination with one or more burners having an inlet, of a manifold for supplying fuel to the burners, means for admitting fuel and air under pressure to said manifold, fuel atomizing instrumentalities in the manifold, conduit means for conducting a mixture of air and fuel in atomized form under pressure from the manifold to the inlet of the burners, a jet having means for varying the rate of flow of atomized fuel into the inlet of the burners, means 40 for controlling the air and fuel ratio to the manifold, means for heating a portion of the air and atomized fuel conduit by the flame of the burners to prevent condensation of the fuel, the air and fuel passing continuously from the manifold to any selected burner or plurality thereof 45 as long as any, or all, of the jets remain open.

9. A hydrocarbon burning apparatus, which comprises the combination with a plurality of burners having inlet openings, of a manifold for 50 supplying fuel to the burners, means for admitting fuel and air under pressure to said manifold, instrumentalities in the manifold for atomizing the fuel into a mist-like form, conduit means for conducting the fuel in mist-like form mixed with 55 air, from the manifold to the burners, jets associated with the conduit means and each directed into a burner, means for controlling the jet to regulate the supply of the said fuel and air mixture to the burners, a portion of said conduit 60 means being so disposed as to receive the heat from the said burners when ignited for heating the said fuel mixture before it passes through the jet, the fuel and air mixture continuing from the manifold as long as all or any one of the jets 65 remains open, and means for controlling admission of fuel and air into the manifold, comprising valves adjacent the fuel and air intakes, and a float for operating the respective valves responsive to changes in level of the fuel in the manifold. 70

10. In a hydrocarbon burning apparatus of the class described, the combination with a plurality of hydrocarbon burners having inlets, of a manifold having air and fuel intakes and having a 75

fuel reservoir for liquid fuel, conduits for delivering fuel and air from the manifold to the burner inlets, means associated with the conduits for controlling the fuel and air supply to the burners, means for controlling the supplies of fuel and air entering the manifold, said means including valves in the fuel and air intakes, respectively, and a float for actuating the said valves responsive to variations in the level of the fuel in the manifold, whereby a lowering of the fuel level and float tends to open the fuel intake valve and close the air intake valve to increase the flow of liquid fuel to restore the fuel level in the manifold, the restoring of the fuel level closing the fuel intake valve and opening the air intake valve.

11. A hydrocarbon burning apparatus having a burner provided with a fuel receiving port and a perforated zone, in combination with a fuel conducting and atomizing system which comprises a manifold, an atomizing instrumentality in said manifold, a conduit for conducting fuel to said manifold, a conduit for conducting air into said manifold, a source of pressure for imposing a pressure upon the fuel and the air travelling through said conduits, valve means in each conduit for varying the amount of fluid admitted to said manifold, a float for operating said valves, a conduit for conducting fuel under pressure from the manifold to the burner port, a jet in said conduit directed toward a burner port, means for varying the opening of the jet to govern the supply of fuel admitted to the burner, said burner and said last named conduit being juxtaposed whereby the flame from the burner impinges on the conduit to heat the fuel mixture before it passes into the burner port.

12. In a liquid hydro-carbon burning apparatus, the combination with a plurality of hydro-carbon burners, burner inlets, atomizers for mixing liquid fuel and air, means comprising a manifold for carrying a supply of said fuel and air under pressure to each of the atomizers, conducting passages extending from said atomizers, said passages having outlets for directing the atomized fuel to said burner inlets for supplying combustion at the burners, means for maintaining an average depth of the fuel in said manifold at each of the atomizers, means for heating the fuel and air mixture before it has passed from said outlets for transforming the mixture into a vaporous condition for operation of the burners and means for supplying under pressure the air which forms part of said mixture and for maintaining a predetermined average air pressure at all times during the flame operation.

13. A liquid fuel burner and fuel conditioning system comprising a reservoir for the supply of liquid hydro-carbon fuel, a burner having an inlet, said reservoir being of any desired capacity and suitable to be located outside of a building or other enclosure, an atomizer suitable to be located inside of a building or other enclosure, means for conducting fuel from said reservoir to the atomizer, means for conducting the supply of air under pressure to the fuel at said atomizer for creating an atomized mixture of the fuel and air, a conducting passage for said mixture extending from said atomizer to said burner inlet, said passage having an outlet, means for heating a portion of said passage for transforming said mixture into a vaporous condition, means including said outlet for injecting the vaporous mixture into the burner inlet for supplying a flame, and means operated by power

automatically controlled for supplying the air which forms part of said mixture and for maintaining a predetermined average amount of pressure of the air throughout the flame operation.

14. A liquid fuel burner and fuel conditioning system comprising means for creating a mist-like mixture of fluid-hydrocarbon and air, means including an inlet for carrying said mixture and additional air to the burner for supplying a flame, a nozzle for injecting said mist-like mixture into said inlet, means comprising a generator through which the mist-like mixture passes to said nozzle, said generator receiving heat of the flame for transforming the mixture into a vaporous condition for further supplying the flame, means for applying under pressure the air which forms part of the mixture and means for maintaining a predetermined average amount of the air pressure throughout the flame operation.

15. A liquid fuel burner and fuel conditioning system comprising means for creating under enclosure and under pressure a mist-like mixture of fluid hydro-carbon and air, means including an inlet for carrying said mixture and additional air to the burner for supplying a flame, a jet for injecting the mist-like mixture into said inlet, means comprising a generator through which the mixture passes and is transformed into a vaporous condition before passing from said jet for further supplying the flame and means for maintaining a predetermined average amount of pressure on the air which forms part of said mixture, said air passing with the fuel to the flame continuously throughout the flame operation.

16. A liquid fuel burner and fuel conditioning system comprising means for creating a mist-like mixture of fluid hydro-carbon and air, means including an inlet for carrying said mixture and additional air to the burner for supplying a flame, a jet for injecting said mist-like mixture into said inlet, means comprising a generator through which the mixture passes to said jet, said generator receiving heat of the flame for transforming said mixture into a vaporous condition, means for changing the air ratio of the fuel and air as required for a combustible mixture after being transformed to a vaporous condition and means operated by power automatically controlled for supplying the air which forms part of said mixture, said air being under pressure throughout the flame operation.

17. A liquid fuel burner and fuel conditioning system comprising means for mixing fluid hydro-carbon with air, a burner having an inlet, a conducting passage comprising a generator and including a jet through which said fuel with air is directed into the inlet for supplying a flame at the burner, means including said burner for directing a portion of the flame against the generator for transforming a further supply of said mixture into a vaporous condition before it has passed from the jet for further operation of the flame and means for maintaining a predetermined average amount of pressure on the air which forms part of said mixture throughout the flame operation.

18. A liquid fuel burner and fuel conditioning system comprising means for creating a mist-like mixture of fluid hydro-carbon and air, said burner having an inlet for receiving said mixture and a plurality of outlets through which the mixture passes to supply a flame, a jet for injecting the

mixture into said inlet, means comprising a generator through which said mixture passes and is transformed into a vaporous condition by heat of the flame before passing from said jet for further supplying the flame and means operated by power automatically controlled for maintaining a predetermined average amount of pressure on the air which forms part of said mixture throughout the flame operation.

10 19. A liquid fuel burner and fuel conditioning system comprising means for creating a mist-like mixture of fluid hydro-carbon and air of a ratio to permit starting a flame, said burner having an inlet, a conduit, said conduit having 15 an outlet for injecting said mixture into the burner inlet, means comprising said conduit and including said flame for heating the further supply of said mixture to transform it into a vaporous condition before it has passed from 20 said outlet, means for changing the ratio of the air to fuel as necessary for a combustible mixture after being heated to a vaporous condition for further operation of the flame and means for supplying under pressure the air which forms 25 part of said mixture and for constantly maintaining a predetermined average amount of said pressure throughout the flame operation.

20. A liquid fuel burner and fuel conditioning system comprising means for creating a mist-like mixture of fluid hydro-carbon and air, said burner having an inlet, a conduit, said conduit

having an outlet for directing the mixture to said inlet for supplying a flame, means comprising said conduit and including heat supplied by the flame for transforming said mixture into a vaporous condition before passing from said outlet 5 for further operation of the flame and means operated by power automatically controlled for supplying the air which forms part of said mixture through all time of the flame operation.

21. A liquid fuel burning and fuel conditioning system, comprising a plurality of burners for combustive operation, said burners being arranged as for cooking or other purposes, a main liquid fuel and air reservoir, an auxiliary liquid fuel and air reservoir, said auxiliary 15 reservoir comprising an outlet means from which the fuel and air may pass for being directed to one or more of the burners, said auxiliary reservoir being disposed externally of the main reservoir, generating means for transforming the fuel 20 and air into a vaporous condition and nozzle means for directing the vaporous fuel and air to one or more of said burners, a motor, means operated by said motor for storing air and fuel in said main reservoir and in said auxiliary reservoir under pressure, the air supplied by said last-named means passing continuously with the fuel to one or more of said burners through all 25 time of the combustive operation.
